United States Patent Office

Des. 203,651
Patented Feb. 8, 1966

203,651

HAT

Irene Stone, 490 Geary St., San Francisco, Calif.

Filed Aug. 30, 1963, Ser. No. 76,413

Term of patent 14 years

(Cl. D3—13)

FIG. 1.

FIG. 2.

FIG. 3.

FIG. 1 is a front perspective view of a hat, showing my new design;

FIG. 2 is a rear perspective view thereof; and,

FIG. 3 is a top plan view of the hat as it appears when untied and in a spread out position.

I claim:

The ornamental design for a hat, as shown.
